Primary Examiner — Deanna L Pratt*Assistant Examiner* — Natasha Vujcic(74) *Attorney, Agent, or Firm* — Perkins IP Law Group LLC; Jefferson Perkins(57) **CLAIM**

The ornamental design for a hitch step, as shown and described.

DESCRIPTION

FIG. 1 is an isometric view of my design, a trailer hitch receiver tongue being shown in broken line as environmental structure;

FIG. 2 is a plan view of my design;

FIG. 3 is a rear view of my design;

FIG. 4 is a side view of my design; and,

FIG. 5 is a front view of my design.

The broken lines in the drawings illustrate the portions of the hitch step that form no part of the claimed design. The bottom of the hitch step is unadorned and forms no part of the claimed design.
